UNITED STATES PATENT OFFICE.

SIMON WREATON BENSON, OF DENVER, COLORADO.

METAL WINDOW-SCREEN.

SPECIFICATION forming part of Letters Patent No. 749,715, dated January 19, 1904.

Application filed March 19, 1903. Serial No. 148,581. (No model.)

To all whom it may concern:

Be it known that I, SIMON WREATON BENSON, a citizen of the United States, residing in the city and county of Denver and State of Colorado, have invented a new and useful 5 Metal Window-Screen, of which the following is a specification.

This invention relates to window-screen frames and similar structures, particularly to 10 devices of this class constructed entirely of metal, and has for its object to produce a structure simple in form and arrangement of parts, which may be adjusted to fit different sizes of window-openings and likewise ad- 15 justed to fit irregularly-formed casings or frames, to adapt the screen-frame to the changes in the interior outlines of window or doorway openings caused by the unequal set- 20 ting of buildings or from other causes.

Another object of the invention is to pro- 25 duce a screen-frame which may be located and operated within comparatively narrow limits—such, for instance, as within the space be- 30 tween the outside blinds and the sash—and without interfering with or affecting the op- 35 eration of either.

Other objects of the invention will appear 40 in the annexed description and be specified in the claims following.

In the drawings illustrating the invention, 45 in which corresponding parts are denoted by like characters, Figure 1 is an elevation of the upper and lower portions of the screen-frame viewed from the interior. Fig. 2 is an ele- 50 vation of the lower portion viewed from the exterior. Fig. 3 is an enlarged cross-sectional detail of the screen-frame on the line 3-3 of Fig. 1. Fig. 4 represents portions of the dis- 55 connected ends of the various rail members 60 forming the frame structure. Fig. 5 is an en- 65 larged cross-sectional detail of the upper mem- 70 ber of the frame, taken on the line 5-5 of Fig. 1 and showing the device applied. Fig. 6 is 75 a view of the upper portion from the outside; 80 and Fig. 7 is a view of the lower portion from the inside, illustrating the construction and 85 mode of attachment when employed upon windows not having outside blinds. Fig. 8 is 90 a plan view of the parts shown in Fig. 6. Fig. 9 is a side view of the parts shown in Fig. 7.

Fig. 10 is a perspective view of the modified form of fastening means shown in Figs. 7 and 9 detached.

In this invention is comprised four primary rail members, four corresponding opposing rail members, the screen material held thereby, the holding-bolts, and the guides or clips by which the frame is supported in place relative to the window frame or casing, the rail members connected at their ends by the holding-bolts or other suitable means passing through elongated apertures to provide for the requisite adjustment of the rail members. The rail members will be of sheet metal bent into the proper shape and preferably of galvanized 65 steel or other metal and preferably coated with non-corrosive material or compounds. The upper, lower, and side primary rail members are designated, respectively, at 10, 11, 12, and 13, overlapping at their ends, as shown, and united, 70 as by bolts or rivets 14, the apertures for the bolts being elongated, as shown, to provide for increasing or decreasing the size of the frame. The outer edges of all the primary frame members are folded transversely from end to 75 end, the inner edges being folded through the greater portion of their length to form inter- 80 mediately-disposed flanges adapted to be en- gaged by the screen material, (indicated at 15,) and the outer folded portions adapted to en- 85 gage the guides 16, attached to the blind-stop 17 of the window-frame, the flanges at the ends of the inner edges being removed. The opposing rail members are indicated, respec- 90 tively, at 18, 19, 20, and 21, overlapped at their ends and united to the primary rail members by the same holding-bolts 14 that hold the latter. The edges of the opposing rail mem- 95 bers are folded transversely thereof reversely to the folded edges of the primary rail mem- 100 bers to form flanges and engage the latter be- 105 tween the folded edges thereof, as shown in Fig. 3, with the screen material held between their adjacent flanges, as shown. By this ar- 110 rangement the screen material is bent over the inner flanges of the primary rail members, and thereby very firmly clamped and held in place when the holding-bolts are operated, the relatively thin material of the sheet metal pressing the screen material very firmly 115

against the flat surface of the primary rail members and coacting with the turned edges of the latter to firmly hold it upon the frame. By this simple arrangement a very strong simple supporting-frame is produced, which thus not only firmly supports the screen material, but which may be adjusted to adapt the screen-frame to various sizes and forms of window-openings. Another advantage gained by this construction is that the screen-frame may be adjusted to fit irregular-shaped openings, so that in event of the window-opening being out of true upon one or more sides the screen-frame may be distorted by loosening the holding-bolts, and the rails independently adjusted at their connected ends to suit the irregular conditions above noted. To more readily accomplish this latter result, the ends of the rail members will preferably be rounded, as shown, so that the joints may be adjusted angularly at the corners without cramping the parts.

The opposing rail members 18 19 20 21 may be of less width than the primary rail members 10 11 12 13 with which they are engaged or of the same width, as may be preferred, and for the purpose of illustration they are shown at the left of the same width, and at the left the member 20 is shown the full width as the member 12, and at the upper part and at the right the parts 18 and 21 are of a less width; but it is to be understood the parts may be constructed of any desired relative width.

35 The lower primary rail member 11 will preferably be wider than the other parts and formed with a central aperture 22 to provide a recess for the holding-catches of the blinds when the screen-frame is employed upon windows having outside blinds, and this aperture will be covered by a shield 24 to prevent the entrance of flies or other insects, the shield being held in place by its upper edge extending between the rail members 19 and 11 and 40 with its lower edge held by the folded lower edge 25 of the member 11, as shown in Fig. 1.

Intermediate bolts 26 may be inserted at such intervals as the size of the screen-frame may require to properly support it and secure 50 the requisite clamping-support to the screen material. In practice these bolts are placed about ten inches apart; but this distance may be varied, as required.

If required, the outer edges of the side rail members 10 13 may be bent to a greater or lesser extent to provide the necessary lateral adjustment instead of depending wholly upon the elongated apertures of the bolts.

When a sliding screen-frame is required, 60 the guides 16 will be employed upon the blind-stops or other parts of the window-frame, and when a stationary screen-frame is required holding means, such as shown in Figs. 6, 7, and 8, will be employed.

The holding means above referred to consists in loops 27, preferably of wire, engaging the upper bolts 14 and extending above the screen-frame and secured in any suitable manner, such as by a hook 28, extending from the blind-stops. By this arrangement it will be 70 obvious that the screen-frame may swing outward at the lower end without displacing it.

The lower edge of the frame is secured by spring-clips 29, attached, as by the lower holding-bolts 14, and extending inwardly and 75 adapted to movably engage a stop-pin 31, extending from the sill 32 of the window. The clips 29 will be formed with sufficient resiliency to engage the pin with a sufficient grip to prevent accidental displacement, but will 80 yield to pressure when the screen-frame is to be detached. By this simple arrangement the screen-frame may be supported detachably in position and easily and quickly removed when desired. The clips and loops may be of any 85 desired size to suit different-sized windows or the different constructions of casings and frames. The clips and loops will generally be employed only upon windows not having outside blinds, but may be employed upon all 90 classes of windows to which they are adapted.

Suitable lifting-handles or "pulls" may be attached to the screen-frame; but as the construction and operation of these devices are so well known they are not illustrated.

The upper edge of the upper primary rail member will be extended laterally, as shown at 30, and adapted to engage the outer surface of the lower cross-bar of the upper sash to form an efficient fly-stop at this point.

By this arrangement a relatively thin screen-frame is produced which may be located in the narrow space between the outside blinds and the sash without interfering with or affecting either, the supports for the screen-frame being attached, as before noted, upon the inner edges of the blind-stops; but while this location is the preferable one it will be understood that I do not wish to be limited thereto or to any other specific location, as the screen-frame may be attached to any desired part of the window frame or casing or in any other opening in the building.

The structure herein described may be employed as a screen-door frame equally as well as for a window-screen frame, and when thus employed suitable diagonal braces will be required to prevent sagging; but this would not be a departure from the principle of the invention, as it would not affect or influence the other portions of the frame.

The outer ends of the rail members 18 19 may be turned transversely to the body of the rail to provide stops to engage the adjacent portions of the supporting structure and prevent undue lateral movement when the device is employed in some localities.

The improved screen-frame may be applied

to doors formed of frames of wood or other material under some circumstances, if required.

The screen-frames may be constructed as cheaply as ordinary wooden frames, and will be very much stronger and more durable and will be practically indestructible, as the screen material, which is the only part which will deteriorate, may be very easily and cheaply renewed without destroying the frame.

This form of screen-frame will be found very desirable by persons who are moving from place to place, as the screen-frames can be very readily removed and readjusted in the new location. Another advantage gained by this arrangement of the frame is that the parts may be readily "nested" or "knocked down," for shipment and assembled only when required for use, and because of the extreme simplicity of the construction the assembling and mounting may be done by persons of ordinary skill and will not require the services of skilled workmen. This is a great advantage, as the screen-frames may thus be manufactured and sold in large quantities and sold as any other merchandise. This adds materially to the value and usefulness of the device, as it can be manufactured almost entirely by machines and in large wholesale lots and handled through the "jobbing trade."

The folding of the frame members greatly increases their strength and enables them to successfully resist the strains to which they will be subjected.

When employed upon windows not having outside blinds, the screen-frames will be secured against the outer surfaces of the outside stops 17, as shown in Figs. 6, 7, and 8, and when thus employed it will be understood the aperture 22 and its cover 24 will not be required.

The cover member 24, it will be noted, is easily removable from the frame when required by loosening the adjacent holding-bolt 26.

Having thus described my invention, what I claim is—

1. A screen-frame having opposing frame members provided with inwardly-extending overlapping adjacent flanges between which screen material may be engaged, and means for adjusting the members to move the flanges thereof in parallel planes.

2. A frame comprising primary rail members having inner clamping edges folded transversely, opposing rail members having inner clamping edges correspondingly folded transversely and engaging said primary rails in the rear of the fold thereon, the screen material held between said adjacent folded edges, and clamping means connecting said rail members, substantially as described.

3. A frame comprising primary rail members having the inner clamping edges folded

transversely, opposing rail members having both edges folded transversely and disposed with one of the folded edges engaging said primary rails adjacent to the folded edges thereof and with the other folded edges engaging the body portions of the primary rails, screen material held between said adjacent folded edges, and clamping means connecting said rail members, substantially as described.

4. A frame comprising primary rail members overlapping at the ends and formed into a rectangular frame, each rail member having its inner edge folded transversely, opposing rail members overlapping at the ends and having their edges reversely folded transversely and engaging said primary rail members with the folded edges thereof adjacent to the folded edges of the primary rail members, the screen material held between said rail members, and holding means connecting said rail members at their ends, substantially as described.

5. A frame comprising primary rail members overlapping at the ends and formed into a rectangular frame, each rail member having its inner edge folded transversely, opposing rail members overlapping at the ends and having their edges reversely folded transversely and engaging said primary rail members with their folded edges adjacent to the folded edges of the primary rail members, the screen material held between said rail members, a plurality of said rail members having elongated apertures at their crossing-points, and holding bolts through said apertures, whereby said screen-frame is laterally adjustable, substantially as described.

6. A frame comprising primary rail members having their ends rounded and overlapping and formed into a rectangular frame, each rail member having its inner edge folded transversely, opposing rail members overlapping at the ends and having their edges reversely folded transversely and engaging said primary rail members with their folded edges adjacent to the folded edges of the opposing rail members, the screen material held between said rail members, and holding means connecting said rail members at their ends, substantially as described.

7. In a screen-frame, a primary rail member having a centrally-disposed transverse aperture and with its inner edge folded transversely and with its outer edge folded into alignment with the body of the rail, an opposing rail member having its edges folded transversely and engaging said primary member, the screen material held between said rail members, a shield over said aperture and held in position with one edge between said rail members and the other edge supported by said folded edge of said primary rail member, substantially as described.

8. A frame comprising primary rail members having inner clamping edges folded trans-

versely, opposing rail members having inner edges reversely folded transversely and engaging said primary rails, the screen material held between the adjacent folded edges, clamping-bolts connecting said rail members at their crossing-points, loops connected to said bolts and extending therefrom, and holding-pins extending from the window-frame and detachably engaging said loops, substantially as described.

9. A frame comprising primary rail members having inner clamping edges folded transversely, opposing rail members having inner edges reversely folded transversely and engaging said primary rails, the screen material held between the adjacent folded edges, clamping-bolts connecting said rail members at their crossing-points, spring-clips connected to said bolts, and stop-pins extending from the window-frame and yieldably engaged by said clips, substantially as described.

10. A frame comprising primary rail members having inner clamping edges folded transversely, opposing rail members having inner edges reversely folded transversely and engaging said primary rails, the screen material held between the adjacent folded edges, clamping-bolts connecting said rail members at their crossing-points, spring-clips formed of a single piece of wire bent to shape and with a loop at one end connected to said bolts and with a loop at the other end yieldably engaging a stop-pin extending from the window-frame and with spring-coils between the looped ends, substantially as described.

In testimony that I claim the foregoing as my own I have hereto affixed my signature in the presence of two witnesses.

SIMON WREATON BENSON.
